MECHANISM FOR FORCING SLIDING DOORS
OPEN AND CLOSEDStacy B. Haseltine, La Grange, Ill., assignor to
W. H. Miner, Inc., Chicago, Ill., a corporation
of Delaware

Application June 20, 1947, Serial No. 756,019

7 Claims. (Cl. 20—23)

1

This invention relates to improvements in actuating means for moving sliding doors of railway cars into and out of the door openings and for forcing the same tightly closed or prying the same partly open.

One object of the invention is to provide in a sliding door structure for railway cars, wherein the door is supported on swinging crank arms slidable on tracks extending lengthwise of the car, a rotary operating bar mounted on the door and having keeper engaging means thereon for forcing the door into and out of the door opening, the rotary bar also serving to actuate certain of the supporting crank arms to swing the same in door opening and closing direction.

Another object of the invention is to provide a mechanism of the character set forth in the preceding paragraph, wherein the operating bar and crank arms have cooperating means thereon for locking the arms in position to hold the door spaced from the wall of the car as the same is slid along the supporting tracks.

A still further object of the invention is to provide a mechanism of the character hereinbefore set forth, wherein the operating bar is provided with keeper engaging means which also serves as means for transmitting motion from the operating bar to the supporting crank arms to swing the same in door opening and closing directions.

Other objects of the invention will more clearly appear from the description and claims herein-after following.

In the accompanying drawings forming a part of this specification, Figure 1 is an elevational view of a portion of one side wall of a railway car provided with a door opening, closed by a sliding door, illustrating my improvements in connection therewith. Figure 2 is a horizontal sectional view, on an enlarged scale, partly broken away, corresponding substantially to the line 2—2 of Figure 1. Figure 3 is an enlarged elevational view of the mechanism at the right hand lower corner section of the door, illustrated in Figure 1, said view being partly broken away, the lower keeper being omitted, and the cover plate of the lower bearing bracket being removed. Figure 4 is a horizontal sectional view, corresponding substantially to the line 4—4 of Figure 3. Figure 5 is a horizontal sectional view, corresponding substantially to the line 5—5 of Figure 3, said view showing the lower keeper. Figure 6 is a view similar to Figure 5, with the keeper omitted, and showing the positions assumed by the parts when the door supporting crank member has been swung outwardly. Figure 7 is a transverse, verti-

2

cal sectional view through the crank arm of the door supporting crank member, said view corresponding substantially to the line 7—7 of Figure 5.

In said drawings, my improved mechanism is disclosed as employed in connection with a well-known sliding door structure, comprising a sliding door 10 adapted to close the door opening 11 in the side wall 12 of a railway car, the door being supported at its front or leading end by swinging crank members 13—13 guided for sliding movement lengthwise of the car on top and bottom tracks 14 and 15, the front or leading end of the door being tiltable toward and away from the car and having forwardly projecting, top and bottom lugs 16—16 having wedging engagement with keepers 17—17 mounted on the wall of the car to cam the leading end of the door into the door opening.

In carrying out my invention, I provide broadly a vertically disposed operating bar A at the rear end of the door 10, an actuating handle lever B for the bar, keeper engaging end members C and D, at the top and bottom ends of the bar, top and bottom supporting guide or bearing brackets E and F, top and bottom keepers G and H, and top and bottom crank members J and K supporting the door for sliding movement on the tracks 14 and 15.

The operating bar A is of the usual well-known design, being of rectangular, transverse cross section and having the keeper engaging end members C and D fixed to the upper and lower ends thereof. As is common practice, the end members are forked to embrace the end portions of the bar and are riveted to the same. The operating handle lever B is of the type commonly employed, being pivoted to the bar A to be dropped to pendant position when the door has been forced open and adapted to be locked in place by the usual latch 18 when the door is closed.

The end members C and D are of similar design, each being provided with a keeper engaging head portion 19 at the outer end and a cylindrical shank 20, intermediate the head 19 and the forked inner end thereof, which is journaled in the corresponding bearing bracket E or F. The keeper engaging head 19 of each end member has a pair of circumferentially spaced, radially projecting lugs 21 and 22 thereon, the lug 21 being in the form of a cam member, which cooperates with the corresponding keeper, as hereinafter pointed out, and the lug 22 being in the form of a rounded tooth. Both of the lugs 21 and 22 of each end member function as gear teeth to transmit mo-

tion to the corresponding crank member J or K, as hereinafter described.

The top and bottom crank members J and K are of similar design, except as hereinafter pointed out. Each crank member comprises a cylindrical shank 23 journaled in the corresponding bearing bracket E or F and an arm 24 extending radially from the outer end of the shank, the arm 24 being of the cross section shown in Figure 7 and having the usual crank pin at the outer end thereof. The crank pin of the arm 24 of the upper crank member J has the usual roller 25 journaled thereon and guided in the upper track 14, which is of channel-shaped form, and the crank pin of the lower crank member K is journaled in a carrier 26 of well-known design, arranged to slide lengthwise on the lower track 15.

The top and bottom bearing brackets E and F are of similar design, each bracket comprising a front plate 27 and a back plate 28. The back plate 28 of each bracket is provided with an outwardly offset, central section 29, and the front plate 27 of each bracket has an outwardly offset section 30 which is engaged over the section 29. The plates of each bracket are clamped together by a bolt 31, which extends through the offset central portions of the plates, and each bracket is fixed to the door 10 by securing elements 32—32 extending through the plates thereof and into the body of the door, the elements 32 thus also serving to clamp the plates together. Each bracket is provided with a pair of vertically extending, laterally spaced bores or bearing openings 33 and 34, which are formed partly in each plate by half bearing seats. The bore or bearing opening 34 of each bracket extends from top to bottom thereof and has the shank 20 of the corresponding end member rotatably supported therein. The top and bottom brackets thus rotatably support the operating bar A on the door 10. The bore or bearing opening 33 of each bracket terminates short of the inner end of the same and has the shank 23 of the corresponding crank member J or K rotatably supported therein. To hold the shank 23 of the crank member against displacement and support said crank member against endwise movement, the same is provided with an annular groove 35 at the extremity thereof, within which is engaged an inwardly projecting, annular rib 135, in the bore 33, formed partly on each plate of the bearing bracket.

At the inner end thereof, each crank member J and K is provided with a pair of circumferentially spaced lugs 36 and 37, which extend radially to the axis of rotation of the shank of the crank member and are adapted to mesh in the manner of gear teeth with the lugs 21 and 22 of the corresponding keeper engaging end member of the operating bar to receive rotary motion from the bar.

The top and bottom keepers G and H, with which the keeper engaging end members C and D cooperate, are of similar design, each keeper being in the form of a casting provided with a laterally opening cam slot or seat 38, within which the cam lug 21 of the corresponding end member is engageable. The cam seat 38 presents a substantially straight, inner, rear wall 39, which is parallel to the wall of the car, and an inner inclined front wall 40 opposed to the wall 39. The lug 21 of the keeper engaging end member is relatively wide, being of the contour most clearly shown in Figures 5 and 6, and having a straight

rear edge 41 merging with a rounded end portion 42, as seen in Figure 5, adapted to have engagement with the flat wall 39 of the keeper to force the door outwardly, and a nose 43 at its forward side adapted to have camming engagement with the inclined wall 40 to cam the door closed. Between the rounded end edge 42 and the nose 43, the edge of the lug 21 is substantially straight and flat, as indicated at 44. The edge 44 is designed to have flat faced engagement with the inclined wall 40 of the cam slot or seat of the keeper to lock the operating bar against rotation when the door is closed. Rearwardly of the cam seat or slot 38, each keeper is cut out or pocketed, as indicated at 143, to provide clearance for the lug 22 of the end member as the bar is rotated.

As hereinbefore stated, the lugs 21 and 22 of each end member are designed to mesh with the lugs 36 and 37 of the corresponding crank member to impart rotation to the latter, the lug 22 engaging with the lug 37, and the lug 21 engaging with the lug 36. As shown in Figure 6, each crank member is provided with an arcuate flange portion 45 extending from the outer side of the lug 36 to the outer side of the lug 37, the end of the flange adjacent the lug 36 being flattened, as indicated at 46, said flattened portion forming a stop face engageable by the lug 21 of the corresponding keeper engaging end member to limit rotation of the operating bar and also limit swinging movement of the corresponding crank member.

The operation of my improved mechanism is as follows: Assuming the door is in the closed position shown in Figures 1, 2, 3, 4, and 5, the lever B, after being unlocked by disengaging the latch 18, is swung from left to right through an arc of 180 degrees, thereby imparting rotation to the same extent to the bar A and the keeper engaging end members C and D in contraclockwise direction, as seen in Figures 4 and 5. The keeper engaging cam lugs 21—21 of the end members are thus swung against the rear walls 39—39 of the keepers G and H to effect outward camming action, thereby prying the rear end of the door out of the door opening. In thus being moved, the door swings about its front end by rocking sliding movement of the lugs 16—16 in the fixed keepers 17—17, the lugs and keepers 16 and 17 acting as separable hinge members. Upon rotation of the bar A, through an arc of approximately 90 degrees, the lugs 21 and 22 of the keeper engaging end members C and D come into mesh with the lugs 36 and 37 of the crank members J and K and the crank members are rotated through the operation of the bar A. Continued operation of the bar to the 180 degrees point of rotation, brings the door to position completely withdrawn from the door opening, with the arms 24—24 of the crank members J and K at right angles to the plane of the side wall of the car, as shown in Figure 6, with the cam lugs 21—21 seated against the flat stop faces 46—46 of the crank members J and K. The bar A is then locked against rotation by swinging the lever B to pendant position into engagement with the usual latch plate 41, as shown in dotted lines in Figure 1, thereby locking the crank members against further swinging movement and maintaining the latter in their right angular position with respect to the side wall of the car.

To further open the door and move the same beyond the door opening, it is manually slid to the right from the position shown in Figures 1 and 2.

In closing the door, the attendant slides the same in front of the door opening, the front end of the door being swung inwardly and the lugs 16—16 thereof into engagement with the keepers 17—17 in the usual well-known manner. After the door has been thus positioned, the bar A is rotated by the operating lever B, thereby rotating the crank members J and K through the medium of the interengaged lugs 21 and 22 of the end members and 36 and 37 of the crank members, swinging the crank members to displace the door inwardly toward the door opening, the bar being rotated in a direction reverse to the rotation thereof during opening movements of the door. The rear end of the door is thus swung inwardly, bringing the keeper engaging cam lugs 21—21 of the bar into operative engagement with the keepers G and H and at the same time unmeshing the lugs 21 and 22 and 36 and 37. The crank members J and K being thus disconnected for operation by the bar A, further rotation of the bar effects independent operation of the keeper engaging cam lugs 21—21 to cam the door inwardly by engagement with the walls 40—46 of the keepers G and H.

I claim:

1. In a door operating mechanism for a sliding door of a container having a wall member provided with a door opening and guide tracks above and below the door opening extending lengthwise of said wall, the combination with top and bottom crank members guided for sliding movement on said tracks and rotatably journaled on the door; of a vertically disposed operating bar rotatably mounted on the door; keepers fixed to the wall of the container above and below the door opening; and interengageable sets of top and bottom radial lugs on said crank members and bar for transmitting rotary motion from the bar to the crank members, one of the lugs of each top and bottom set of said bar being engageable with the corresponding keeper for forcing the door into and out of the door opening.

2. In a door operating mechanism for a sliding door of a container having a wall member provided with a door opening and a guide track extending lengthwise of said wall member, the combination with a crank member guided for sliding movement lengthwise of said track and rotatably journaled on the door for supporting the same; of a rotary operating bar journaled on the door; a keeper fixed to said wall member; and interengageable sets of radial lugs on said crank member and bar for transmitting rotary motion from the bar to the crank member, one of said lugs of said bar having camming engagement with the keeper for forcing said door into and out of the door opening.

3. In a door operating mechanism for a sliding door of a container having a wall member provided with a door opening and guide tracks above and below the door opening extending lengthwise of said wall, the combination with top and bottom crank members guided for sliding movement on said tracks and rotatably journaled on the door; of a vertically disposed operating bar rotatably mounted on the door; keepers fixed to the wall of the container above and below the door opening; top and bottom, radially projecting keeper engaging lugs on said bar engageable with said keepers for forcing the door into and out of the door opening; additional top and bottom, radial lugs on said bar circumferentially spaced from said first named lugs; and top and bottom,

circumferentially spaced lugs on said crank members engageable by the first and second named lugs of the bar to receive rotary motion from said bar.

5. In a door operating mechanism for a sliding door of a container having a wall member provided with a door opening and a guide track extending lengthwise of said wall member, the combination with a crank member guided for sliding movement lengthwise of said track and rotatably journaled on the door for supporting the same; of a rotary operating bar journaled on the door; a keeper fixed to said wall member; a radial cam lug on said bar engageable with the keeper for forcing said door into and out of the door opening; a second radial lug on said bar circumferentially spaced from said first named lug; and radially projecting, circumferentially spaced lugs on said crank member engageable by said first and second named lugs of the bar to receive rotary motion from said bar.

6. In a door operating mechanism for a sliding door of a container having a wall member provided with a door opening and guide tracks above and below the door opening extending lengthwise of said wall, the combination with top and bottom crank members guided for sliding movement on said tracks and swingingly journaled on the door to support the same; of a vertically disposed operating bar rotatably journaled on the door; top and bottom keepers on the container above and below said door opening; keeper engaging cam members on the top and bottom of said bar engageable with the keepers for forcing the door into and out of the door opening; and locking faces on said cam members engageable with said crank members for limiting swinging movement of the latter.

7. In a door operating mechanism for a sliding door of a container having a wall member provided with a door opening and a guide track extending lengthwise of said wall member, the combination with a crank member guided for sliding movement lengthwise of said track and swingingly journaled on the door to support the same; of a vertically disposed operating bar rotatably journaled on the door; interengaging means on said bar and crank members for transmitting rotary motion from the bar to said crank members; top and bottom keepers on the container above and below said door opening; keeper engaging cam members on the top and bottom of said bar engageable with the keepers for forcing the door into and out of the door opening; and locking faces on said cam members engageable with said crank members for limiting swinging movement of the latter.

8. In a door operating mechanism for a sliding door of a container having a wall member provided with a door opening and a guide track extending lengthwise of said wall member, the combination with a crank member guided for sliding movement lengthwise of said track and swingingly journaled on the door; of a rotary operating bar journaled on the door; a keeper fixed to said wall member; a keeper engaging cam lug on said bar engageable with the keeper for forcing said door into and out of the door opening; and stop means on said cam lug engageable with said crank member for limiting swinging movement of the latter.

STACY B. HASELTINE.
